J. A. HEWETT.
HYDROCARBON BURNER.
APPLICATION FILED APR. 14, 1917.

Patented Aug. 21, 1917.

FIG. 1.

FIG. 2.

FIG. 3

John A. Hewett
Inventor

By *Geo. H. Kimmel*

Attorney

UNITED STATES PATENT OFFICE.

JOHN A. HEWETT, OF MIDLOTHIAN, TEXAS.

HYDROCARBON-BURNER.

1,237,904.

Specification of Letters Patent. Patented Aug. 21, 1917.

Application filed April 14, 1917. Serial No. 162,037.

To all whom it may concern:

Be it known that I, JOHN A. HEWETT, a citizen of the United States, and resident of Midlothian, in the county of Ellis and State of Texas, have invented certain new and useful Improvements in Hydrocarbon-Burners, of which the following is a specification.

This invention relates to new and useful improvements in hydrocarbon burners, and 10 the primary object of the invention is to provide a novel and improved burner for coal oil, petroleum, or other liquid fuel.

Another object of the invention is to provide a hydrocarbon burner of this character 15 that is provided with a pair of retorts and a deflector in connection therewith which is adapted to direct the flames, and spread the same in such a manner that the retorts and main feed pipe will be thoroughly 20 heated to vaporize the fuel before the same is discharged.

Still another object of the invention is to provide a hydrocarbon burner of this character adapted to be positioned in the conventional type of wood or coal stove, with 25 no material change to the structure thereof.

A still further object of the invention is to provide a device of this character which is easily and simply constructed, inexpensive 30 to manufacture, and one which will be very efficient in operation.

With these and numerous other objects in view my invention consists of the novel features of construction, combination and arrangement of parts which will be herein-referred to and more particularly pointed out in the specification and claims.

In the accompanying drawing:

Figure 1 is a plan view of the burner positioned in a conventional type of cooking stove;

Fig. 2 is an elevational view of the burner, showing one of the retorts, and a portion of the support in section, and

Fig. 3 is a transverse section taken through the retorts.

In describing my invention I shall refer to the drawing in which similar reference characters designate like and corresponding parts throughout the several views. As shown in Fig. 1 the burner is placed in the conventional type of wood or coal burning cooking stove, the same being of such a size that it is easily placed therein when the lids 55 are moved from the stove.

The burner is provided with a right angular support 1, having an upright portion 2, and a flat horizontally extending portion 3, that is recessed longitudinally as shown at 4 for a purpose to be hereinafter more fully 60 described.

The burner proper comprises a main feed pipe 5, that is bent intermediate its ends as shown at 6, with its side portions extending in substantially parallel spaced relation, the 65 side portions thereof being designated by the numerals 7 and 8. This main feed pipe is substantially U-shaped, and is disposed normally horizontally. The main feed pipe 5 is connected at one end with a fuel supply pipe 9, that carries the fuel from a supply tank 10, that may be positioned at any desired distance from the burner, or the most available place. The connection between the supply pipe 9 and the main feed 70 pipe 5 has a control valve 11, whereby the flow of fuel to the burner may be adjusted. An additional control valve 12 is positioned 75 in the connection between the supply pipe 9 and the fuel holding tank 10.

The supply pipe is connected with the side portion 7 of the main feed pipe 5, as clearly shown in Fig. 1 of the drawing, while the free end of the opposite side portion 8 of said main pipe is provided with 80 a discharge pipe 13, that has a laterally and downwardly extending portion 14 connected with said side portion, and a parallel horizontally extending portion 15 positioned in the longitudinally extending recess in the portion 3 of the support. The extremity of this parallel portion, which portion is positioned centrally between the side portions 7 and 8, and in a plane beneath the same, is bent upwardly as shown at 16, 85 and is provided with a burner head 17 thereon. This burner is approximately midway between the opposite ends of the side portions, as clearly shown in Fig. 2 of the drawing.

Holding bolts 18 are connected with 100 the parallel portion 15 of the discharge pipe, and the bent portion 6 of the main feed pipe, said bolts being positioned through the portions 3 and 2 of the support 1 respectively. These bolts are of the conventional type as 105 shown in the accompanying drawing, but it will be understood that if desired any other type of fastening means may be employed.

The main superheating feature of this type of burner includes a pair of trans- 110

versely alined and spaced retorts 19, which are positioned or interposed in the side portions 7 and 8 of the main feed pipe respectively. These retorts may be of any size, 5 corresponding to the size of the burner, and the same are surrounded by a deflector strip 20, as clearly shown in Fig. 3 of the drawing. This strip 20 extends across between the side portions 7 and 8 of the pipe 5, and 10 over the burner 17.

In operation, after the burner has been started, it is obvious that the flame that is fed from the burner 17, will strike the deflector strip 20, and hence will be spread 15 around the retorts 19, so as to thoroughly heat the same, and cause vaporization of the fuel that is fed therethrough. The flame will also be deflected around the main feed pipe 5, so that the same acts as a super- 20 heater for the oil in addition to the retorts. The flow of fuel through the burner is controlled by the valve 11, that may be adjusted by hand so as to permit the requisite amount of oil or other liquid fuel to flow 25 therethrough. This control valve 11 is preferably disposed through one side of the stove in which the burner is positioned, so that the same is easily accessible for operation. The support 1 on which the burner is positioned, 30 is disposed in the stove in any desired manner. This type of burner is easily and simply constructed, and the coacting retorts that are associated with the main feed pipe, in combination with the spreader or de- 35 flector that surrounds said retorts, will form a very efficient type of burner, that will absolutely vaporize the liquid fuel that flows therethrough, before the same is discharged through the burner 17.

40 From the foregoing description of the construction and operation of my new and improved hydrocarbon burner for coal oil, petroleum, or other liquid fuel, the manner of applying the same to use and the opera- 45 tion thereof will be readily understood, and it will be seen that I have provided a sim-

ple and efficient means for carrying out the objects of this invention.

Having fully described my invention, what I claim as new, and desire to secure by Letters Patent, is:

1. A liquid fuel burner including a right angular support, a substantially U-shaped main supply pipe having its connected ends secured to the upright portion of the support, an inlet control valve in one end of said main pipe, a discharge pipe on the other end of said main pipe extending laterally and downwardly and bent parallel with the main pipe intermediate the side 55 portions, means to secure said parallel portion of the discharge pipe to the horizontally extending section of the support, a burner on the extremity of the discharge pipe, a pair of transversely alined retorts in the 60 side portions of the main pipe adjacent the burner, and a deflector carried by said retorts and extending between the same over the burner.

2. A liquid fuel burner including a substantially U-shaped horizontally disposed main feed pipe, an inlet control valve in one end thereof, a discharge pipe on the other end of said main pipe extending laterally and downwardly and bent parallel with the 75 main pipe intermediate the side portions, a burner on the extremity of said discharge pipe, a retort in each side portion of the main pipe, and a deflector carried by said retorts and disposed over the burner. 80

3. A liquid fuel burner including a substantially U-shaped horizontally disposed main feed pipe, a cylindrical retort in each side portion of said pipe, a branch discharge pipe having a burner disposed between said 85 retorts and beneath the same, and a strip surrounding the two retorts and extending between the same to form a deflector disposed over the burner.

In testimony whereof, I affix my signature 90 hereto.

JOHN A. HEWETT.
